(57) **CLAIM**

I claim the ornamental design for a control panel for power supply (II), as shown and described.

DESCRIPTION

FIG. 1 is a front perspective view of a control panel for power supply (II) showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front end view of the control panel for power supply (II) in accordance with my design, shown in its environment thereof.

The broken lines are for the purpose of illustrating environmental structure and form no part of the claimed design.
